(57) **CLAIM**

The ornamental design for an adhesive backing for a dog bone blister of a blister pack, as shown and described.

DESCRIPTION

FIG. 1 is a top perspective view of an adhesive backing for a dog bone blister of a blister pack, showing our new design; FIG. 2 is a bottom perspective view of the adhesive backing illustrated in FIG. 1;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.

Any broken lines in the drawings are for illustrative purposes only and form no part of the claimed design.
